LIFE PRESERVER

Carl M. Weinheimer, Kenmore, N. Y.

Application May 5, 1943, Serial No. 485,741

10 Claims. (Cl. 9—17)

This invention relates to life preservers and particularly to a compact collapsible form of life preserver.

An object of the invention is to provide a life preserver that will occupy a very small space when not in use and therefore can be carried in the pocket of a coat or a fishing kit.

A further object is to provide in a container a collapsed life preserver that will instantaneously expand into operative buoyant condition upon the release of the container cap and which is made ready for use by the attachment of the cap to the base of the container.

A further object is to provide a life preserver which may readily be collapsed when not in use and automatically filled with air under atmospheric pressure when prepared for normal use.

A further object is to provide a life preserver which in use is normally filled with air under atmospheric pressure, with means whereby such pressure may be increased in order to insure complete expansion of the life preserver in order to obtain maximum buoyancy.

A further object is to provide a self-contained life preserver unit wherein all of the operative parts are permanently attached to each other, thereby eliminating the possibility of loss of any part.

With these and other objects in view the invention consists of other novel features which will be more fully described in the specification and claims.

In the drawing:

Fig. 1 is a vertical sectional view of the life preserver collapsed in the container with the central portions of the sleeve and spring illustrated diagrammatically.

Fig. 2 is a top plan view of the life preserver fully expanded but shown in reduced size and with the central portion of the sleeve and spring broken away to indicate that they are of greater length than as illustrated;

Fig. 3 is a diagrammatic plan view of the life preserver ready for use with the cap attached to the base of the container; and,

Fig. 4 is a fragmentary sectional view showing a modified form of means for attaching the cap to the base of the container.

Referring in detail to the drawing, 1 designates generally a container made of metal, plastic or other suitable waterproof material having a cylindrical side wall 2; a base 3; and a cover or cap designated generally 4. Formed adjacent each end of the cylindrical side wall 2 are externally threaded portions 5 and 6. In the

construction shown in Figs. 1, 2 and 3 the threaded portion 5 constitutes an annular flange which extends below the base 3. The base 3 is provided with a valve closure washer 7 which may be made of leather, rubber, or other suitable material and which is attached to base 3 by any suitable adhesive or other means. Cap 4 has a wall 8 with a centrally located valving aperture 9 and internally threaded annular flange members 10 and 11.

The life preserver proper is designated as 15 and comprises an elongate tubular member or sleeve which is flexible and waterproof. It may be made of suitable fabric that has been waterproofed or of a semi-rubber compound or synthetic fabric or rubber compound. One end of the sleeve 15 is attached to the inner surface of the cylindrical wall 2 adjacent the base of the container 1 by an adhesive or other suitable means, as indicated at 16. The other end of sleeve 15 is attached to wall 8 of cap 4 by an adhesive or other suitable means as indicated at 17. The attachment of the sleeve at 16 must be complete around the entire circumference in order that there be no leakage of water or air into the interior of the sleeve at the point of attachment, and the attachment of the other end of the sleeve 15 to the cap at 17 shall likewise provide a water- and air-tight connection with the cap.

Within the sleeve 15 is located an expandible spring member 18 having one end bearing against the base 3 and the other end bearing against the wall 8 of cap 4. This spring member is of sufficient diameter and has a sufficient number of coils so that it will force the sleeve 15 to expand to its limit, both longitudinally and circumferentially.

Between the point of attachment of sleeve 15 with container 1 at 16 and the base 3 of the container there is provided a conduit 21 having an opening 22 from the atmosphere to the interior of the container and sleeve. The opening 22 is provided with any conventional form of valving mechanism which will permit a person to blow through the valve, thereby forcing air into the container and sleeve; the valve construction, however, being such as to prevent the emission of air from the interior of the container out to the atmosphere. In Fig. 1 a flexible flap valve 23 is shown, the valve being merely fastened to flange 24 of conduit 21 at one edge thereof, whereby it may flap open inwardly to admit air to the conduit but is normally held closed by air pressure within the conduit.

Instead of the construction shown it is obvious that sleeve 15 could be attached to base 3 and an extension of conduit 21 provided so as to have an opening leading directly into the interior of sleeve 15.

In Fig. 4 the container 1 is shown as being provided near its base 3 with an annular detent 25 over which can be snapped an annular bead 26 formed on a flange of cap 4. If desired, a bead similar to 26 could be used in place of the threads 10 on the portion of the flange on the opposite side of wall 8 of the cap, and in such case the cylindrical wall of container 1 adjacent the open end would be provided with a complementary annular detent similar to that shown at 25. In the construction of Fig. 4 it is apparent that a washer much thinner than that shown at 7 could be attached externally to base 3.

In the operation of the life preserver Fig. 1 shows the device as it would normally be carried in a coat pocket, fishing kit or other article customarily carried onto a boat. The sleeve 15 and spring 18 have been collapsed or compressed by pressure against cap 4 and rotation of the same in screwing it into a fixed position on container 1. It will be noted that the interior of sleeve 15 is open to the atmosphere through aperture 9, thereby permitting the escape of air during such closing operation.

In case of an emergency when it is desired to use the life preserver the cap is unfastened from the container and spring 18 immediately forces the sleeve to fully expand, air entering into the interior of the sleeve through the aperture in the cap. The cap is then brought around to the base of the container and there screwed on the base, the threads 11 of the cap engaging the threads 5 on the container side wall adjacent the base, and the washer 7 closing the aperture 9 and thereby preventing the admission of further air or of any water through the aperture and preventing the escape of air from the interior of the sleeve.

The user of the life preserver may, if desired, blow through the valve 21 and thereby slightly increase the pressure of air within the sleeve and insure that the sleeve will be circumferentially expanded and that thereby the utmost buoyancy will be obtained.

In addition to the cap locking means shown in Figs. 1 and 4, it should be understood that any one of a number of other conventional forms of locking means might be utilized.

It will be understood that the device herein shown and described is merely illustrative of the preferred embodiment of the inventive principles involved and that these principles may be otherwise embodied without departing from the spirit of the invention or the scope of the appended claims.

What is claimed is:

1. A life preserver comprising a collapsible elongate sleeve of waterproof material, spring means for expanding said sleeve to its full length and diameter, a container for said sleeve, said container having a cylindrical wall provided adjacent each end with cap securing means, a base having a washer externally mounted thereon, and a cap, one end of the sleeve being attached to the interior of the container adjacent the base, and the other end of the sleeve being attached to the interior of the cap, said cap having a wall with a valving aperture opening into said sleeve and a marginal flange provided with securing means thereon for engaging selectively with the

securing means on said cylindrical wall, whereby said sleeve may be held in non-operative collapsed condition within the container by securing the cap to the open end of the container or held in expanded operative condition by attaching the cap to the base end of the container, the washer on the base closing the valving aperture in the cap wall.

2. A life preserver comprising a collapsible elongate sleeve of waterproof material, spring means for expanding said sleeve to its full length and diameter, a container for said sleeve, said container having a cylindrical wall provided adjacent each end with cap securing means, a base having a washer externally mounted thereon, and a cap, one end of the sleeve being attached to the interior of the container adjacent the base, and the other end of the sleeve being attached to the interior of the cap, said cap having a wall with a valving aperture opening into said sleeve and a marginal flange provided with securing means thereon for engaging selectively with the securing means on said cylindrical wall, whereby said sleeve may be held in non-operative collapsed condition within the container by securing the cap to the open end of the container or held in expanded operative condition by attaching the cap to the base end of the container, the washer on the base closing the valving aperture in the cap wall, and valving means mounted on the container wall near the base and opening into the sleeve whereby air may be blown into the sleeve to insure the complete expansion thereof.

3. A life preserver comprising a collapsible elongate sleeve of waterproof material, spring means for expanding said sleeve to its full length and diameter, a container for said sleeve, said container having a cylindrical wall provided adjacent each end with cap securing means, a base having a washer externally mounted thereon, and a cap, one end of the sleeve being attached to the interior of the container adjacent the base, and the other end of the sleeve being attached to the interior of the cap, said cap having a wall with a valving aperture opening into said sleeve and a marginal flange provided with securing means thereon for engaging selectively with the securing means on said cylindrical wall, whereby said sleeve may be held in non-operative collapsed condition within the container by attaching the cap to the open end of the container or held in expanded operative condition by securing the cap to the base end of the container, the washer on the base closing the valving aperture in the cap wall, and valving means mounted on the container wall near the base and opening into the interior of the container between the base and line of attachment of the sleeve and cylindrical wall, whereby air may be blown into the sleeve to maintain the complete expansion thereof.

4. A life preserver comprising a collapsible elongate sleeve of waterproof material, spring means for expanding said sleeve to its full length and diameter, a container for said sleeve, said container having a cylindrical wall provided adjacent each end with cap securing means, a base having a closure for a cap valving aperture externally mounted thereon, and a removable cap having a wall with a valving aperture for admitting air to said sleeve and a marginal flange provided with securing means for engaging selectively with the securing means on said cylindrical wall, said sleeve having one end attached to the interior of the container adjacent the

base and the other end attached to the interior of the cap and surrounding the valving aperture.

5. A life preserver comprising a collapsible elongate sleeve of waterproof material, coil spring means within said sleeve for expanding said sleeve to its full length and diameter, a container for said sleeve, said container having a cylindrical wall provided adjacent each end with cap securing means, a base having a cap valving closure externally mounted thereon, and a cap having a wall with a valving aperture opening for admitting air to the sleeve and a marginal flange provided with securing means thereon for engaging selectively with the securing means on said cylindrical wall, one end of the sleeve being attached to the interior of the container adjacent the base and the other end of the sleeve being attached to the interior of the cap and surrounding the valving aperture in the cap, and supplemental valving means mounted on the container wall near the base for admitting air into the sleeve.

6. A life preserver comprising a collapsible elongate sleeve of waterproof material, a container therefor having side and bottom walls and a cover element, said cover element being removable to open said container, one end of said sleeve being secured about its edge to the interior face of said cover element and the other end of said sleeve being secured about its edge to the interior of said container, valved passage means for admitting air to said sleeve when the same is expanded by withdrawal from said container by movement of said cover element away from said container, and means on said cover element for securing to an outside wall of said container to form a closed loop for encircling the body of a user.

7. A life preserver comprising a collapsible elongate sleeve of waterproof material, a container therefor having side and bottom walls and a cover element, said cover element being removable to open said container, one end of said sleeve being secured about its edge to the interior face of said cover element and the other end of said sleeve being secured about its edge to the interior of said container, valved passage means in said cover element for admitting air to said sleeve when the same is expanded by withdrawal from said container by movement of said cover element away from said container, and means on said cover element for securing to an outside wall of said container to form a closed loop for encircling the body of a user.

8. A life preserver comprising a collapsible elongate sleeve of waterproof material, a container therefor having side and bottom walls and a cover element, said cover element being remov-

able to open said container, one end of said sleeve being secured about its edge to the interior face of said cover element and the other end of said sleeve being secured about its edge to the interior of said container, valved passage means in said cover element for admitting air to said sleeve when the same is expanded by withdrawal from said container by movement of said cover element away from said container, and means on said cover element for securing to an outside wall of said container to form a closed loop for encircling the body of a user, and a second valved passage means for admitting air through a container wall and into the sleeve.

15 9. A life preserver comprising a collapsible elongate sleeve of waterproof material, spring means within the sleeve for normally expanding the same, a container for said sleeve having side and bottom walls and a cover element, said cover
20 element being removable to open said container, one end of said sleeve being secured about its edge to the interior face of said cover element and the other end of said sleeve being secured about its edge to the interior of said container,
25 valved passage means in said cover element for admitting air to said sleeve when the same is expanded by the spring means upon removal of said cover element from said container, a valving element externally mounted on a container wall, and means on said cover element for secure-
30 ment to the exterior of a wall of said container over said valving element to close the passage through the cover element and to form a closed loop for encircling the body of a user.

10. A life preserver comprising a collapsible elongate sleeve of waterproof material, spring means within the sleeve for normally expanding the same, a container therefor having side and bottom walls and a cover element, said cover element being removable to open said container, one end of said sleeve being secured about its edge to the interior face of said cover element and the other end of said sleeve being secured about its edge to the interior of said container, 40 valved passage means in said cover element for admitting air to said sleeve when the same is expanded by the spring means upon removal of said cover element from said container, a valving element externally mounted on a container wall, 45 and means on said cover element for securement to the wall of said container over said valving element to close the passage through the cover element and to form a closed loop for encircling the body of a user, and a second valved passage 50 means for admitting air through a container wall and into the sleeve.

CARL M. WEINHEIMER.
